(57) **CLAIM**

The ornamental design for the shoe, as shown and described.

DESCRIPTION

FIG. 1 is a perspective view of the first embodiment of a shoe showing our new design.

FIG. 2 is a right-side perspective view thereof.

FIG. 3 is a left-side perspective view thereof.

FIG. 4 is a front perspective view thereof.

FIG. 5 is a rear perspective view thereof.

FIG. 6 is a top perspective view thereof; and,

FIG. 7 is a bottom perspective view thereof.

Any broken lines, colors, and/or patterns in the drawing are for illustrative purposes only and form no part of the claimed design.
